DESIGN FOR A DRESS ENSEMBLE

Jacob Moskowitz, New York, N. Y.

Application January 29, 1942, Serial No. 105,505

Term of patent 3½ years

To all whom it may concern:

Be it known that I, Jacob Moskowitz, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my design;

Fig. 2 is a rear view of Fig. 1;

Fig. 3 is a front view of the dress member of the ensemble shown in Fig. 1;

Fig. 4 is the rear view of the dress member of the ensemble shown in Fig. 1.

I claim:

The ornamental design for a dress ensemble, substantially as shown.

JACOB MOSKOWITZ.
